UNITED STATES PATENT OFFICE.

SAMUEL T. YOUNG, OF MCKEESPORT, PENNSYLVANIA.

DESIGN FOR A VEHICLE-TIRE.

SPECIFICATION forming part of Design No. 31,831, dated November 14, 1899.

Application filed October 14, 1899. Serial No. 733,676. Term of patent 7 years.

To all whom it may concern:

Be it known that I, SAMUEL T. YOUNG, a citizen of the United States of America, residing at McKeesport P. O., general delivery, in the county of Allegheny and State of Pennsylvania, have produced a certain new and original Design for Vehicle-Tires; and I do hereby declare the following to be a full, clear, and exact description thereof, reference being had to the accompanying drawings, which form a part of this specification.

My invention relates to a new and original design for pneumatic vehicle-tires, and consists of an annular tube or tire having two annular ribs or beads encircling the inner periphery and an annular strip arranged intermediate of the said beads, as will be fully described hereinafter.

In the drawings, Figure 1 is a side elevation of a vehicle-tire, showing my design. Fig. 2 is an enlarged sectional perspective view of a portion of the same.

The leading features of my design are the solid strip extending continuously around the

inner side and the flaring ribs or beads at 25 either side and parallel therewith.

A represents the pneumatic tube, which is of the class known as "single-tube" variety.

B is the solid inner peripheral strip, elevated a slight distance above the surface of 30 the tube A and formed integral therewith. This strip extends continuously about the tube, and at either side of the same is a bead or protruding rib C, which extends about the tire parallel to the said strip and formed rounding upon the outer edges and undercut beneath, as is best seen by reference to Fig. 2 of the drawings.

What I claim is —

The design for a vehicle-tire, substantially 40 as shown and described.

In testimony whereof I have hereunto affixed my signature in the presence of two subscribing witnesses.

SAMUEL T. YOUNG.

Witnesses:

JOHN DOWNEY,
JAMES J. CLOONAN.
